DEWAXING OF OILS

Hardin B. McDill, P.O. Box 654, Houston, Tex.

No Drawing. Filed June 26, 1957, Ser. No. 668,041

4 Claims. (Cl. 195—3)

This invention relates to processes for dewaxing oils and refers more particularly to a process for dewaxing any wax-containing oil, including both vegetable oils and mineral oils, by the use of enzymes or yeast.

Petroleum waxes

Petroleum is the major source of hydrocarbons. The composition of crude petroleum is very complex. It is made up of hundreds of different compounds. In addition to small percentages of nitrogen, sulphur and oxygen-bearing compounds present in some petroleums, the hydrocarbon content may include paraffins, straight and branched-chain types; traces of olefins and other unsaturated aliphatic hydrocarbons; naphthenes or cycloparaffins of the generic formula C_NH_{2N-6} , having five or six carbon atoms in the ring, with paraffinic or naphthenic side chains and aromatic or benzene hydrocarbons of generic formula C_NH_{2N-6} . Higher molecular weight hydrocarbons include cycloparaffin-aromatic structures with paraffinic side chains. The composition varies with the source. Pennsylvania oils have a high content of paraffinic hydrocarbons with a residue of soil paraffins. Mid-Continent oils have a higher naphthenic and aromatic hydrocarbon content, and Russian oils consist mostly of naphthenic hydrocarbons.

The commercial isolation of hydrocarbon fractions consists of a series of distillations of crude petroleum and subsequent washings and purifications. The lowest liquid fraction, boiling range under 20°, consists mainly of butane and pentane. The next fraction, petroleum ether, boiling range 35 to 80° is chiefly pentane and hexane.

Gasoline, because of its extensive demand, may be collected over a wide boiling range, 40 to 215°. Gasoline embraces a wide range of hydrocarbons, saturated and unsaturated, branched and straight chain, up to $C_{12}H_{26}$.

Kerosene is the hydrocarbon fraction collected at from 175 to 275°, and comprises $C_{12}H_{26}$ to $C_{16}H_{34}$ compounds. Gas oil, collected above 275°, includes light household burning oils, heavier furnace oils and power generating oils such as diesel oil. They are graded on the basis of volatility, viscosity, and ignition characteristics.

For some types of petroleum, further distillation under steam superheating yields the heavy distillate, from which paraffin waxes, lubricating oils and some light and medium viscosity mineral oils are obtained. For Pennsylvania and Mid-Continent oils, the residue, after fuel oil distillation, is utilized as a source of lubricating and mineral oils, paraffin wax and petrolatum. This residue is vacuum distilled under steam injection at about 315° yielding "wax distillate" and a nonvolatile residue.

The wax distillate is chilled (minus 3°) under 300 pounds' pressure and filter pressed, effecting a partial separation of oil and wax. The waxy material is then "sweated" or warmed in shallow pans or dissolved in

2

benzene or other solvents and chilled, permitting a further separation of oil from paraffin. The latter is then filtered hot through charcoal and cast into blocks, resulting in the familiar crystalline paraffin utilized for paper coating, candles and pharmaceutical ointment bases. The oil filtrate from paraffin presses is steam distilled, and the residual oil purified by filtration through bleaching clays, yielding high grade lubricating stock oils and heavy mineral oil. (Textbook of Organic Medicinal and Pharmaceutical Chemistry—Wilson and Gisvold, 3rd ed., 1956, J. B. Lippincott, pp. 60, 61.)

Vegetable oils and waxes

Fats and oils are found widely distributed in nature, in both the plant and animal kingdoms. Waxes likewise are natural products but differ slightly from the fats and oils in their basic composition. Whereas the fats and oils are mixtures of the glycerides of various fatty acids, the waxes are mixed esters of higher polyhydric alcohols other than glycerol with fatty acids.

The various natural oils differ in regard to their fatty acid content. These acids fall within (1) the saturated series as exemplified by stearic acid and are the basis for the nondrying oils, the (2) mono olefinic series with one double bond between carbons as illustrated by oleic acid and the (3) polyolefinic series with more than one such double bond as exemplified by linoleic and linolenic acids. The latter two classes of acids, being unsaturated, furnish the semidrying and drying oils, according to the amounts of unsaturation present. The chief constituents of the vegetable oils are the 16 and 18 carbon acids. Coconut oil is unique in that it consists of esters of much shorter carbon chain acids, the 12 and 14 carbon acids being present in greatest amounts.

The factor determining whether one of these compounds is termed a fat or an oil is merely its melting point. The degree of unsaturation of the acids involved effects the melting point of the ester mixture, the more unsaturated acids giving esters with lower melting points, these being the chief constituents of the oils.

There are two broad classifications for oils: edible and inedible. The various edible oils, cottonseed, olive, soybean, corn, etc., are employed for salad dressings, other table uses, and for cooking purposes. The hydrogenated fats for cooking and baking, such as Crisco and Spry, may include a wide variety of vegetable oils, such as cottonseed, peanut, and soybean, since the hydrogenating process removes the color, flavor and odor of the original source.

The two general methods conventionally employed in obtaining vegetable fats and oils are expression and solvent extraction. Cottonseed oil is used for shortenings, margarine and salad or cooking oils. Corn oil is used almost exclusively as a salad oil. Only coconut oil of low free fatty acid content is employed for edible purposes. Peanut oil is hydrogenated and refined for use in the manufacture of margarine, salad and cooking oils, and in some vegetable shortenings. The finest grade of castor oil is reserved for medicinal purposes. Soybean and linseed oils are also of interest.

Ozocerite is the name given to certain naturally occurring mineral waxes. The ozocerite known commercially is a particular earth wax which is mined in Eastern Europe, but important similar waxes are mined elsewhere. One variety, mined in Utah, is known as Utah wax or Utah ozocerite. The name montan wax generally applies to the wax obtained from a bituminous wax, solvent extracted from bituminous lignite or shale, but a similar wax may be obtained from peat or brown coal. (The Chemical Process Industries, R. N. Shreve, 1956, McGraw-Hill, pp. 595-610.)

Ozocerite is composed of ester waxes, such as montan wax, straight chain hydrocarbon waxes such as paraffin wax and branched chain hydrocarbon waxes. Montan wax ($C_{28}H_{56}O_2$) comprises esters of montanic acid.

Dewaxing oils

The dewaxing of oils is a critical problem both in the fields of vegetable oils and mineral oils. In the purifying or refining of vegetable oils, and especially edible vegetable oils, the extraction of waxes from the individual oils has not developed as successfully as has this process in the mineral oil field and several oils have not been fully exploited as to their commercial uses because of this problem. Many of these waxes are very tenacious in their adherence to their oil bases or carriers and resist even successive attempts to extract the wax. Rice oil, for example, is one which contains a relatively large percentage of wax which is extremely difficult to remove and thus has not yet been completely evaluated as to its potential uses because of this fact, commercially. The methods of chilling and settling and solvent extraction have been attempted in removing or attempting to remove waxes from vegetable oils. These have met with varying degrees of success, as previously noted.

As to the mineral oils, in the refining of petroleum, it is well known that crudes from certain geographical regions have more or less wax therein. Various processes have been developed to do this, including chilling, settling and centrifuging and solvent extraction employing various solvents. While it must be admitted that, largely, the removal of waxes from petroleum and mineral oils is presently successfully accomplished, such removal is achieved at great expense and requires much time, as well as expenditure of energy.

The main objection to the presence of wax in petroleum products is its relatively high congealing temperature which interferes with the free circulation of oil in the engine. After circulation is established, the engine performance depends upon the true viscosity of the oil and not the pour point. At temperatures of complete miscibility, the presence of wax in the oil may even be beneficial. Dissolved wax improves the viscosity index, lowers the carbon forming tendencies and has a minor effect on the other oil properties. Nevertheless, due to the temperature difficulties, in the majority of petroleum products, the presence of wax is regarded as a severe disadvantage and problem.

Therefore, an object of the invention is to provide a process of dewaxing oils which will swiftly, easily and cheaply remove waxes from wax-containing oils.

Another object of the invention is to provide such a process which will dewax oils of either vegetable or mineral source, including the edible vegetable oils and the petroleum oils.

Another object of the invention is to provide a method of dewaxing wax-containing oils of either vegetable or mineral origin by the addition of relatively small quantities of easily obtainable chemical substances and biochemical substances thereto.

Another object of the invention is to provide such a process for dewaxing wax-containing oils wherein there is no problem of separating the dewaxing chemical substances from the treated oils after the dewaxing process.

Still another object of the invention is to provide a process for dewaxing wax-containing oils of either vegetable or mineral origin wherein the addition of certain by-products of enzymatic activities to the oil to be dewaxed effectively removes a large proportion of the wax in the oil in the first stage of the process and wherein in the oil, after the first separation may be retreated by the same process to remove yet further oil so that the process will substantially and completely dewax wax-containing oils.

Yet another object of the invention is to provide a process for dewaxing oils of either vegetable or mineral

origin which will substantially and completely remove waxes from these oils whereby to obtain color and clarity in the dewaxed oils at least equal to the best dewaxing processes now existent and in most cases far superior thereto.

Another object of the invention is to provide a process for dewaxing wax-containing oils of either vegetable or mineral origin which will remove waxes from oils which have previously not been successfully dewaxed either 10 experimentally or commercially.

Still another object of the invention is to provide a treatment process for crude mineral oils and petroleum with yeast wherein not only is the crude dewaxed but at least a partial separation of the hydrocarbon fractions 15 is achieved without the application of heat to the crude or the use of expensive distillation equipment.

Other and further objects of the invention will appear in the course of the following description thereof.

I have discovered that waxes can be removed from 20 oils by fermentation treatment employing yeast and/or enzymes. The waxes removed include the paraffinic waxes from petroleum distillates or crudes and, as well, the mixed esters of higher polyhydric alcohols with fatty acids which make up the waxes from vegetable oils, and 25 particularly, edible vegetable oils.

A specific example of the dewaxing process applied on a laboratory scale operation utilizing an edible vegetable oil is as follows:

(1) $\frac{1}{6}$ oz. of yeast is dissolved in 50 cc. of water and 30 sweetened with a little sugar to assist the fermentation action (2 oz.) which takes place in the succeeding steps.

(2) The foregoing cc. solution is added to 5 gallons of crude rice oil.

(3) The foregoing mixture is agitated vigorously for 35 several minutes at room temperature (approximately 80° F.).

(4) 6 drops of pepsin are added and agitation is continued for several minutes.

(5) Agitation is discontinued. The mixture is allowed 40 to stand for a period varying from a minimum of 24 hours to a maximum of approximately six days during which continued fermentation causes almost all of the wax to settle out.

(6) The bulk of the wax-free oil can be decanted from 45 the vessel and the balance is separated from the wax and yeast residue by centrifuging; the oil obtained by centrifuging can be added to that which was decanted.

(7) The oil thus recovered is essentially wax-free but, as a precautionary measure, it may be retreated in the 50 same manner as the original crude oil, beginning with the addition of the sweetened yeast solution and pepsin, followed by agitation, settling and, finally, separation of any additional residue from the supernatant oil.

The process as applied to mineral oils, either crude or 55 distillate fractions, is exactly the same as previously described as regards the order of steps and the yeast, sugar and pepsin. The results will be exactly the same, although the time intervals may be slightly different. Therefore, I will not repeat the individual steps just recited, but 60 incorporate them with the differences noted in this paragraph to provide specific examples of the application of the method to mineral oils.

I have discovered that the critical factor in the pepsin addition is the enzyme peptase or pepsin. Pepsin, the 65 enzyme, is remarkable in having an isoelectric point which is at least as far acid as pH 1. The optimum pH for the enzyme is also in the strongly acid region, being 1.5 to 2.5. Elixir of pepsin is composed of the following:

70	Pepsin	grams	35
	Citric acid	do	12
	Sodium phosphate	do	13
	Distilled water	cc	300
	Glycerin	cc	200
75	And additional distilled water to 1,000 cc.		

My process will dewax oil from the following vegetable seeds, nuts and the like: cottonseed, peanut, corn kernels, soybeans, olives, coconuts, linseed, tung nuts, castor beans, palm kernels, sesame seed, flax seed, babassu, copra, rice, hemp seed, kapok seed, perilla seed, sugar cane and rape seed. This list is not intended to be limiting.

The known art on dewaxing rice oil reveals the following: rice bran contains 15 to 18 percent rice polishings, 20 percent of oil. The yield of wax recovered, if recovered from the crude rice oil, is somewhat less than 2 percent or less than .04 of one percent on a bran basis. The oil may be at least partially dewaxed before refining with acid and alkali by the use of a De Laval separator or basket centrifuge. The oil can also be at least partially dewaxed by the use of evacuated unglazed porcelain cylinders covered with filter cloth. A good yield is obtained at 20-25° centigrade with suction at 50 mm. mercury pressure. These studies of rice bran wax were made on the tank settling from crude rice bran oil. (Cousins, E. R., et al., Journal of American Oil Chemical Society, vol. 30, 9-14, 1953.)

Other art states that the crude wax-containing glycerides may be separated from crude rice oil by wintering at 20-25° C. and then treated with a solvent such as 5 percent methanol in commercial N-hexane to effect a sharp separation of soluble and insoluble parts. Without the use of the solvent, the wax from the tank settling cannot be effectively separated by filtration methods. Studies have been made of the use of acetone and isopropanol as extracting solvents for tank settling. It should be pointed out, however, that, despite these statements in the art, there is no commercial method to satisfactorily extract rice oil wax from the rice oil and yet leave a clear, properly colored oil which will not cloud on reduction of temperature due to the presence of yet additional wax therein.

The chemical composition of rice bran wax comprises esters of waxy acids of 22, 24 and 26 carbons combined with alcohols of 26, 28 and 30 carbons. It also contains small amounts of wax acids of 28, 30 and 32 carbons. The softer constituents contain both saturated and unsaturated acids of the range C-14 to C-20. The wax also contains sterols.

The crude rice wax may be at least partially purified by washing repeatedly with methyl alcohol, ether, and, finally, chloroform. This process yields a substance which is an ester mainly composed of tetracosanoic acid and myricyl alcohol ($C_{31}H_{63}OH$) with small amounts of saturated acids and some unsaturated acids.

Rice wax analysis characteristics: percentage of free fatty acids 2.1-7.3, average 3.8; iodine number 11.1-19.4, average 15.2; percentage of unsaponifiable 55.6-67.0, average 58.1; saponification number 56.9-104.4, average 80.7; percentage of phosphorus .01-18, average .09; percentage volatile matter .38-2.94, average .94; melting point (drop) degrees centigrade 75.3-79.9, average 77.9; softening point degrees centigrade 74.3-79.0, average 76.5; hardness by durometer: average 100.

The chemical composition of the various types of waxes show pronounced differences comprising a wide range of chiefly aliphatic compounds from hydrocarbons to esters including pseudo-esters, alcohols, ketones and ethers. More recently, attempts have been made to produce sugar cane wax on a large scale. This wax, which might be obtained in almost unlimited quantities, has as such, unsatisfactory properties. Efforts are now being made to improve them by removing the undesirable fatty constituents inherent in crude wax.

The biological generic term for yeast is *Saccharomyces cerevisiae*.

My present concept of the nature of my process is that the enzymes in the yeast and the fermentation products may satisfy some of the unsaturated bonds of the lower alcohols in the rice wax and the unsaturated hydro-

carbon bond in the lubricating oil wax. Such a reaction may change the crystalline structure of the components of the wax and in the higher molecular weight compounds, the crystals may become denser and heavier.

5 This theory is not intended to be limiting.

Yeast enzymes (a partial list):

(1) Diastase—conversion of starch to sugar;
(2) Cytase—conversion of cellulose to sugar;
(3) Invertase—conversion of polysaccharides to

10 monosaccharides;

(4) Maltase—conversion of maltose to dextrose;

(5) Milibiase—conversion of milibiose to dextrose;

(6) Lactase—conversion of lactose to dextrose;

(7) Zymase contains four elements—alcoholase, oxidase, endo-triptase and peptase, these are analyzed below.

15 (7a) Oxidase—enzymes of this class are considered to be active in the oxidation changes induced in a number of organic substances, such as sugars, aldehydes, alcohols and fats. The oxidase (oxidase) secreted by acetic acid bacteria is well known for its energetic oxidation of alcohol to acetic acid in the manufacture of vinegar. Yeast oxidase is assumed to take an active part in building plasma and autofermentation. Its presence is indicated by the heat generated when air is passed through finely divided yeast.

20 (7b) Endo-triptase—the proteolytic endo-enzyme of yeast is able to hydrolyze the protein molecule to amino acids and basic substances. It is considered to be active in the digestion of protein food, the formation of plasma and in regulating the protein content of the cell. Endo-triptase is precipitated from yeast juice with alcohol but cannot be separated from invertase. It is most active at 45° C. in 2% solution of hydrochloric acid and is destroyed at 50° C. Endo-triptase plays an important part 25 in autofermentation of yeast.

30 (7c) Peptase—this enzyme acts upon the proteins of malted grain, changing them by hydrolysis into peptones and polypeptides. Its action is promoted in the mash by the presence of a small amount of lactic acid. Peptase 35 may be extracted from green malt and is most active at temperatures ranging from 38° C. to 54° C. It is destroyed at 68° C.

35 The following conditions must be met for the process to be effective. In the first place, the yeast must be living. In the second place, carbohydrate which the yeast 40 will accept as food must be added to maintain the fermentation action. Thirdly, the additional peptase or pepsin must be added. The live yeast and excess peptase must be agitated in the oil. Finally, a certain amount of 45 settling time must pass. When these conditions are satisfied, the process which I have disclosed will effectively and completely dewax oils of the various kinds set forth 50 previously in one or more treatments.

55 The best test for determining the presence of wax in vegetable or mineral oils after dewaxing processes is, either freezing the oils or subjecting the oils to successively varying temperatures ranging from very cold to very warm. Either or both of these processes will cause the oil to either cloud or precipitate additional wax if the liquid is not completely dewaxed. With my inventive 60 process, provided the conditions described above are met and, provided successive treatments are given, if the quantity or type of oil requires, will result in providing vegetable or mineral oils which will freeze clear and thaw 65 clear from the freezing and, as well, not precipitate wax or cloud under conditions of severally varied temperatures.

I have also observed that, after the application of my 70 process as above described to crude mineral oil or petroleum, a series of layers appear to the naked eye in the settled, treated body of petroleum oil. At present, under visual inspection alone, I have been able to identify at least six such layers.

(1) The bottom layer is a yellowish one made up of what appears to be the yeast fillers and carriers which are 75 generally starches of various types.

(2) Immediately above the preceding layer I find a blackish, dark layer which very probably are impurities of various sorts together with, probably, asphalts and the like.

(3) Above the preceding layer is what appears to be a kerosene-gasoline layer which is generally about 25 to 30 percent of the total volume of the treated settled crude petroleum and which has a grayish color after the practice of my method.

(4) Above the foregoing layer is a Whitish layer which I am unable to identify at present.

(5) Above the foregoing layer is a layer of generally brownish wax.

(6) Above the wax layer is a layer which appears to be and which I take to be gums of various sorts somewhat similar in appearance to the wax previously mentioned.

(7) At the top of all these layers is found the clear, dewaxed, degummed oil.

These various layers can be decanted off or drawn off by various conventional means. The exact composition and components of these various layers I do not know completely at this date, aside from the above speculations, but it is my belief that my method, as well as providing an efficient dewaxing process, is applicable as well as a crude oil component separating process or fractionating process which requires no application of heat or expensive apparatus and equipment. The provision of such a separation in the oils treated is thus one of the main features of my invention.

From the foregoing it will be seen that the invention is one well adapted to attain all of the ends and objects hereinbefore set forth, together with other advantages which are inherent to the method.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter hereinabove set forth

is to be interpreted as illustrative and not in a limiting sense.

Having thus described my invention, I claim:

1. A process of treating an oil containing at least one wax therein comprising adding living *Saccharomyces cerevisiae* yeast, peptase in addition to any peptase in the yeast and a carbohydrate the yeast will accept as food thereto cause a physical separation of at least a portion of the wax from the oil.
2. A process of treating an oil containing at least one wax therein comprising adding living *Saccharomyces cerevisiae* yeast, peptase in addition to any peptase in the yeast, and a carbohydrate the yeast will accept as food thereto to cause a physical separation of at least a portion of the wax from the oil, separating the wax produced by the first addition from the oil and adding living *Saccharomyces cerevisiae* yeast, peptase in addition to any peptase in the yeast, and a carbohydrate the yeast will accept as food again to the separated oil to cause a physical separation of additional wax from the oil.
3. A process of treating an oil containing at least one wax therein comprising adding living *Saccharomyces cerevisiae* yeast, peptase in addition to any peptase in the yeast, and a carbohydrate the yeast will accept as an energy source thereto, agitating the oil containing the yeast, peptase and carbohydrate to mix them thoroughly therein and cause a physical separation of at least a portion of the wax from the oil and removing the wax produced from the oil.
4. A process as in claim 3 wherein the wax removal process comprises letting the wax produced settle and then decanting the oil therefrom.
